UNITED STATES PATENT OFFICE.

VINCENT LOMBARDI, OF BROOKLYN, NEW YORK.

KNITTING MACHINE.

Application filed July 5, 1924. Serial No. 724,510.

This invention relates to knitting machines, and more particularly it relates to machines for knitting multi-color fabrics.

An object of this invention is to provide a machine capable of automatically knitting fabrics of a predetermined pattern which may comprise yarns of different colors assembled in the fabric to present any arrangement desired.

Another object is to control independently and automatically the movement of each dial needle of a circular knitting machine.

Another object of the invention is to provide means, preferably automatic, for changing the character of the stitch at such predetermined times as may be desired.

Another object is to provide means for transferring the stitch from a cylinder needle to a dial needle of a circular knitting machine.

Another object is to provide a machine capable of knitting a new type of stitch from yarns of different colors having many advantages over stitches of previous types.

Another object is to provide a unitary control means for all the dial needles in a circular type of machine.

Still other objects will be apparent from the detailed description hereinafter given.

These objects in the preferred form of this invention are embodied in a double knitting machine of the circular type employing both cylinder and dial needles.

Special cams and other mechanisms are provided to produce the various results desired and reference is made to the detailed description for their nature.

The invention may be fully understood by reference to the following detailed description taken in connection with the accompanying drawings, in which Figure 1 represents in plan view one form of this invention; Figure 2 represents a sectional view of the knitting machine of Figure 1; Figure 3 is a detail showing of a control member of the machine; Figure 4 is a schematic lay-out of the cams for controlling the cylinder needles of the machine; Figure 5 is a schematic showing of the various cams for controlling the dial needles of the machine; Figure 6^a is an enlarged sectional view of the control arrangement for the dial needles; Figures 6^b, 6^c, and 6^d represent the apparatus of Figure 6^a in different positions of the knitting cycle; Figure 6^e is a modification of the apparatus of Figure 6^a; Figures 7^a, 7^b, and

7^c illustrate how the cylinder and dial needles cooperate to form the new stitch of this invention; Figure 8 illustrates schematically the character of one type of fabric that may be knitted by the machine of Figure 1 including portions involving the novel stitch and other portions being of a predetermined pattern; Figure 9 illustrates a pattern paper which may be employed in controlling the dial needles; Figure 10 represents in perspective the novel stitch of this invention; Figure 11 indicates in perspective the pattern portion of the fabric; Figure 12 represents in plan view a modified type of knitting machine having certain features not present in the machine of Figure 1; Figure 13 illustrates the control means for the dial needles of the machine of Figure 12; Figure 14^a is an enlarged sectional view of a dial needle control arrangement; and Figures 14^b and 14^c show the apparatus of Figure 14^a in various positions of a knitting cycle.

The knitting machine of Figure 1 is of the jacquard type, employing both cylinder needles and dial needles, that is, both horizontal and vertical rows of needles. The machine specifically shown is adapted to function with three types or colors of yarn, and for convenience yarn 1 will be assumed to be red yarn, yarn 2 will be white yarn, and yarn 3 will be blue yarn. The machine is adapted for multi-color knitting, and as many different yarns as may be desired may be used.

Power for driving the machine is obtained by means of a shaft 30 ending in a cog wheel 31 engaging teeth along the lower side of a large rotatable annular ring 32. Teeth on the outer edge of ring 32 mesh with a cog wheel 33 which by a vertical shaft is connected with cog wheel 34 which engages with teeth around the periphery of another rotatable annular ring 35. A stationary annular ring 36 is located between members 32 and 35. The vertical or cylinder needles, such as needle 37, operate in grooves on the inner side of a stationary cylinder 38, while the necessary cams for operating the cylinder needles are mounted on the outer surface of a rotatable cylindrical ring 39. The ring 39 is supported by upright members fastened to the spider 40, which has arms extending and fastened to the upper horizontal rotatable ring 35. The spider member is suitably rotatably mounted about a central vertical shaft 42. The horizontal or dial needles 43

rest in grooves or slots in the stationary dial 36.

The cylinder 39 and annular rings 35 and 32 are assumed to rotate in a counter-clockwise direction.

The cams for operating the dial needles are either supported from the arms of the spider 40 or by the rotating annular ring.

Means are provided for controlling independently the operation of each dial needle, whereby patterns or special stitches may be knitted by the machine automatically according to a predetermined plan. Each dial needle (see Fig. 6^a) is provided with a control member 44 which determines whether or not the associated needle will be in a position to form loops when the yarn carrier goes by the needle. Each control member 44 comprises a portion 45 located in a slot or groove in the stationary dial 36 but free to move back and forth in the slot and also free to have a certain angular movement in a vertical plane. This angularly movable portion 45 is pivoted about a push rod 46 and is free to slide along a certain length of the push rod from shoulder 47 to shoulder 48. A coiled spring 49 located in a slot in member 45 and extending between the end of push rod 46 and a pin on member 45 tends to force the end of member 45 against shoulder 47 of push rod 46 for reasons described later. The opposite end of push rod 46 passes freely through an aperture in stationary dial 36 out beyond its outer circumference.

On line with the outer ends of the push rods 46 is a rotating cylindrical drum 50 having parallel rows of apertures, each row having an aperture for a push rod immediately opposite thereto. Passing around the rotating drum 50 is a punched pattern paper strip 51 having apertures registering with the apertures in the drum 50. The operation of a dial needle therefore depends upon whether or not, when the control member 44 is pushed outward by suitable cams, the outer end of the push rod 46 encounters an aperture in the paper pattern.

In the machine shown in Figure 1, each drum and paper pattern takes care of one seventh of the push rods for the dial needles since seven drums are distributed around the circumference of the machine. These drums are supported from the main body of the machine in any suitable manner. Each drum is independently stepped around to line up the ends of the push rods with the next row of apertures in the drum by means about to be described and the description that follows is applicable to any of the drums shown in Figure 1.

Each drum has a toothed wheel such as wheel 55 engaging a worm wheel 56 mounted on a shaft 57, the other end of which has a three-toothed cog wheel 58, see Figure

2. This shaft 57 is rotatably supported by the support 60, suitably fastened to the outer part of the stationary dial 36. The movable dial 35 has mounted thereon at two positions 180 degrees apart three spaced projecting arms 61, 62, and 63 (see Figure 1), which are adapted to engage the toothed wheel 58 so that every time these three projections pass a toothed wheel 58, the shaft 57 is rotated through 360 degrees. One complete rotation of shaft 57 is designed to turn the cylindrical drum 50 a distance sufficient to have the push rods line up with the next row of apertures in the cylinder 50. Each cylindrical drum 50 will be moved two steps for every complete revolution of the rotatable dial 35. It will be noted that one set of projections 61 to 63 pass each cog wheel 58 after the carrier for the blue yarn 3 has passed and before the carrier for the red yarn 1 passes. The other set of projections 61 to 63 pass the cog wheel 58 after the red yarn carrier has passed. These two sets of projections set the paper pattern for the red and blue yarn carriers but not for the white yarn 2 since the white yarn is not knitted by the dial needles. It follows from this that there should be a set of projections 61 to 63 for each yarn carrier carrying yarn to be knitted by the dial needles.

As stated previously, the machine of Figure 1 is adapted to knit either a special pattern, as determined by the paper pattern strip 51, or else to knit a novel stitch, as will hereinafter be described. The change of the knitting from the regular stitch to the novel stitch or vice versa is accomplished by a special mechanism, as shown in Figures 1 and 2. Mounted on the shaft 30 is a worm wheel 65 engaging a toothed wheel 66 fixed to a shaft on which is mounted an eccentric which drives the pawl 67 in a well known manner.

This pawl 67 serves to step around a ratchet wheel 68 mounted on the same shaft as a sprocket wheel 69 engaging the links of a chain 70. Certain links of the chain 70 bear cams 71 which are capable of striking and lifting the pivoted arm 72 to raise shaft 73 and cause member 74 to come in the path of an upward projecting portion 110 of the rotating latch member 76 to cause it to hook with the latch 75, the long arm of member 76 being moved so as to rotate plate 77 in a counter-clockwise direction. This plate 77 has around its outer edge cam surfaces which cause the pivoted arms 78, 87 and 88 to raise or lower the cylinder needle cams 85, 83 and 80. These cams are mounted on suitable vertical shafts 90, 91 and 92, which are normally maintained biased to one position by suitable compressed springs shown in Figure 4. Cams 80 and 83 are biased to their uppermost positions, as shown schematically in Figure 4, which illustrates

the various cams for the cylinder needles. The rotation of latch members 76 in a clockwise direction causes plate 77 to rotate in a counter-clockwise direction and causes cam surfaces 94, 95 and 96 to operate the pivoted arms 88, 87 and 78 to lower cams 80 and 83 to their lowermost positions and to raise cam 85 to its uppermost position. This movement of the cams changes the character 10 of the stitch, as will hereinafter be described. When the control member 74 is in its lowermost position, shown in dotted lines in Fig. 2, the rotating dial carrying the latch 75 causes the downward projecting portion 111 of latch 75 to strike control member 74, thereby releasing latch 76 and allowing it to be restored by the action of spring 97. This will rotate plate 77 in a clockwise direction and cause cams 80, 83 and 85 to be 15 restored to their biased positions, so as to change the character of the stitch again. The post 98 insures that the latch member 76 will always be restored to the same position since the spring 97 will always pull the member 76 until it strikes the post 98. The change from one kind of knitting to the other therefore depends on the presence or absence of cams in the links of chain 70. For portions of the chain 70 having no cams, 20 the knitting will be of one type, while the portion with cams will mean knitting of another type.

Three yarn carriers for yarns 1, 2 and 3 for the machine are shown in Figures 1 and 4. For purposes of convenience, it will be assumed that these yarns are red, white and blue, respectively, and they are so labeled in the drawing. Projections, such as 113 and 114, on the three yarn carriers serve to 25 secure a positive opening of the needle latches in the well known manner.

The functions of the various cams for the cylinder needles will now be explained, reference being made to Figures 1 and 4. The heavy dotted line of Fig. 4 represents 30 the position taken by the needle butts as the various cams pass with these cams in their full line positions of Figure 4, that is, their biased positions, as mentioned above. The cams pass from right to left, as shown in Figure 4. Cam 79 serves to raise the needles, a projection 113 on the red yarn carrier serving to open the latches. Cam 80 has no effect on the needles in its upper position so the needles after catching the yarn 35 1 remain up. The yarn 1 falls below the open latches at this time and is caught at predetermined points by the dial needles, as will be explained later. Cam 81 also performs no function at this time, but after the needles have caught the white yarn 2, cam 82 contacts with the needle butts and lowers the cylinder needles, forming loops of the white yarn. Cam 83 then raises the needles, 40 45 the hooked white yarn 2 causing the latches to open and the white yarn falls below the latch. This serves to separate the white and red yarns to enable the dial needles to be inserted therebetween, as will be explained later. Cam 84 now lowers the cylinder 50 needles and the white yarn slips over the needles. Cam 85 being in its lower position, does not cause the cylinder needles to catch the blue yarn 3. Cam 79 then raises the needles as before and the process is repeated. This, in combination with the action of the dial needles, produces a new stitch, which 55 will be described later.

When cams 80, 83 and 85 are in their dotted line positions of Figure 4, the cylinder 60 needles form ordinary loops of all three yarns. Cam 79 raises and cam 80 lowers the needles to form loops of the red yarn 1. Cams 81 and 82 cause white yarn loops to be formed. Cams 83 and 84 perform no 65 function at this time. Cams 85 and 86 cause loops of yarn 3 to be formed.

The dial needles which alternate in position with the cylinder needles are operated as follows, it being understood that every 70 dial needle is between two adjacent cylinder needles and every cylinder needle is between two dial needles as is customary in the art. Referring more particularly to Figure 5, it 75 will be assumed for the purpose of Figure 5 that the cams are moving from left to right, although, of course, the cylinder needle cams and the dial needle cams rotate in a counter-clockwise direction, as shown in Figure 1. A convenient place to start in the cycle is with 80 cam 12, which serves to push outwardly all of the needle control members 45. This outward movement of members 45 will cause the rods 46 to engage the paper pattern 51, certain of the rods passing through the 85 pattern and drum where there are apertures, while the other rods will press against the paper, the outward movement of members 45 being taken up by the compression of the springs 49. As soon as cam 12 has passed 90 the compressed springs on the rods which did not pass through apertures will cause these preselected members 45 to be moved inwardly again to their position as before the passing of cam 12, while the members 45 with 95 uncompressed springs will remain in their outward position. The passing of cam 12 therefore separates the control members 45 into two groups. Those members 45 which were restored by the release of the springs 100 will be raised by the passing of cam 13 so that when cam 5 later passes, they are moved inwardly and the inner ends come in contact with the ends of the corresponding needles 105 to push these needles inwardly. Only those needles are pushed inwardly which correspond to control rods which during the passing of cam 12 were not pushed through apertures in the paper pattern 51. This inward 110 movement of certain needles is sufficient to 115 120 125 130

bring the moved needles under the control of cam 8, which contacts with the needle butts and pushes the needles farther in a distance sufficient for them to catch the yarn which is 5 passing. As shown in Figure 1, there is a cam 8 opposite the red yarn 1 carrier and a similar cam 8' opposite the feeding point for the blue yarn 3, but no such cam is associated with the white yarn 2. Hence, with the 10 cams arranged as in Figures 1 and 5, the dial needles will knit only red and blue loops. The passing of cam 8 will therefore cause the chosen dial needles to catch the red yarn 1, after which cam 4 will cause the needles to 15 be pushed outwardly again. Before cam 4, however, acts to retract the needles, cam 11 serves to lower all of the control members 45 below the level of the needles so when the needles are retracted by cam 4 the ends of 20 the needles and members 45 will overlap, without contacting, the end of the needle lying above its control member. Cam 7 then contacts with the needle butts to advance the needles slightly to relieve the tension on the 25 loops held by the needles. Those control members 45 which passed through apertures in the pattern 51 are now removed and pushed inwardly by cam 10. The cycle of 30 operations has now been completed and the fingers 61 to 63 located above cam 10 will cause the drum 50 to be rotated one step to bring the next row of perforations in paper 51 into play. Cams 12', 13', 5', 8', 4', 11' and 10' will now come successively into 35 action to cause loops of the blue yarn 3 to be knitted, after which cams 12, 13, 5, 8, 4, 11 and 10 repeat the above process.

The manner in which a pattern may be 40 knitted by the machine of Figure 1 may now be explained, assuming the pattern is like that illustrated schematically in Figure 8, wherein the pattern part of the cloth is located between lines 121 and 122, the parts of the cloth not lying between these lines 45 being made according to a special stitch to be hereinafter described. The distance between two adjacent horizontal lines in Figure 8 may be taken as representing a row of loops. As illustrated in Figure 4, the 50 cylinder needles, when cams 80, 83 and 85 are in their dotted line positions, knit loops of all three yarns and the loops formed by the cylinder needles are in the back of the 55 fabric while the knitting by the dial needles lies in the front of the fabric, the dial needles knitting only red and blue loops. It is understood, of course, that the cams 80, 83 and 85 are in their dotted-line positions of 60 Figure 4 for the pattern portion of the fabric between lines 121 and 122 of Figure 8, while these three cams are in their full line positions of Figure 4 for the portion of the fabric of Figure 8 outside of lines 121 and 122.

65 In Figure 8 the white portion between

lines 121 and 122 will represent red loops of 70 yarn 1 in the front of the fabric, while the inked portions will represent blue portions of 75 yarn 3. The first row of loops below the point 121 is all red yarn 1. Hence, the portion 124 of the pattern paper 51 (which may be assumed to be the portion determining the character of the loops in the first row below point 121 by proper cooperation with the dial push rods 45) will have no apertures 80 since every dial needle should form a loop, providing the yarn carrier which will pass for that pattern setting is the red yarn carrier. That is, it is assumed that the portion 124 of the pattern 51 of Figure 9 is 85 opposite the dial needle push rods 45 at the time of the passing of the red yarn carrier by one pattern 51 of Figure 1. The second row of loops 123 of Figure 8 is also all red so the pattern 51 in row 125 has an aperture 85 for every needle push rod controlled thereby to prevent the formation of any blue loops as the blue yarn carrier passes. Then the pattern 51 in row 126 has no apertures so 90 that when the red yarn carrier comes around, all red loops will be formed in the front of the fabric to correspond to row 123 of the fabric, while row 127 of the paper pattern will have an aperture for each needle push rod so that no blue loops will be formed by 95 the dial needles at this time. The next row 150 of the cloth has two separated blue loops and the rest are red. Hence, the portion 128 of the paper pattern which is effective 100 when the red yarn carrier is passing has apertures where no red loops are desired and no apertures where red loops are desired. The next portion 129 of the paper pattern, however, which is effective when the blue 105 yarn carrier is passing has apertures except at the places where blue loops are desired. Hence, row 150, due to portions 128 and 129 of the paper pattern, will comprise all red loops except at two separated places where blue loops will be located. Row 151 of the 110 cloth has two loops of blue at the left and three loops of blue in the center. Hence, the part 130 of the pattern paper for the red 115 yarn carrier will have apertures only where the blue loops are desired, while the part of the pattern just below, namely, row 131, will contain apertures only where the red loops are desired.

It therefore will be apparent on examination of the pattern, such as the part 120 between 124 and 133 of Figure 9, that the parts 124, 126, 128, 130, 132 and 134, designed to work with the red yarn carriers, have apertures where red loops are not desired and have no apertures where red 125 loops are desired, while for the parts 125, 127, 129, 131, 133, etc. for the blue yarn carrier, apertures indicate no blue loops, while no apertures indicate blue loops. Hence, the pattern 51 enables each dial needle to be 130

independently controlled by the presence or absence of apertures in the pattern paper. Therefore, the pattern paper may be designed to produce by the machine of Figure 5 any pattern of cloth desired, the design of the fabric of Figure 8 being only illustrative. The pattern paper for each of the seven drums 50 of Figure 1 may be so designed to cooperate with adjacent pattern papers as to 10 give a continuous design around the machine of any desired type or configuration.

At the same time as the dial needles are knitting red and blue loops in the front of the fabric, according to the design on the 15 pattern paper, the cylinder needles are knitting in turn loops of all three yarns, which lie at the back of the fabric.

Figure 11 illustrates more in perspective the fabric knitted by the machine in developing the pattern. The blue yarn 3 is shown 20 heavily shaded, the red yarn 1 is only slightly shaded, while the white yarn 2 is unshaded. The front of the fabric faces the observer and the large loops of red and blue 25 yarn in the front of the fabric will be easily noticed. These are the loops knitted by the dial needles. The loops formed by the cylinder needles lie at the back of the fabric and between adjacent wales of the loops 30 knitted by the dial needles. The pattern thus stands out very prominently.

As was previously explained, the parts of the schematic showing outside of lines 121, 122 of Figure 8 represent the new stitch 35 which is illustrated in perspective in Figure 10. The manner in which the stitch is made is shown in Figures 7^a, 7^b and 7^c. The novelty in the stitch resides mainly in the special manner in which the cylinder 40 needles are operated. The pattern paper for the dial needles may, for example, be of the type shown above row 124 in Figure 9. The first row 160 of Figure 9, which is effective when the red yarn carrier is passing, indicates that alternate dial needles will form 45 red loops, the remaining dial needles not being projected inwardly to catch the red yarn, while when the blue yarn carrier comes around row 161 of the pattern indicates that 50 the said remaining needles will form blue loops, while the dial needles that caught the red will not catch the blue yarn. Thus, it will be understood that considering the left 55 of Figure 7^a alternate loops that are just visible will be red and the remaining blue. Starting with the left of Figure 7^a, it will be remembered that the dial needles knit only red and blue loops, while the cylinder needles knit loops of only the white yarn 60 because cams 80 and 85 are in their full line positions of Figure 4. Cam 79 is just beginning to raise the cylinder needles while cam 8 is causing the preselected dial needles 65 (alternate as shown in row 160 of Fig. 9) to be projected inwardly. The projection

on the yarn carrier now opens the latches for both the cylinder and dial needles. The cylinder needles are not immediately lowered because cam 80 is in its full line position of Figure 4. The red yarn merely falls on the 70 outside of the cylinder needles, as shown in the middle of Figure 7^a, while the projected and alternate dial needles catch the red yarn and pull it through the old loops due to the action of cam 4.

By scanning the nature of 75 the pattern in Figure 9, it will be seen that the needles now forming the red loops have just previously formed blue loops so that the red yarn in Figure 7^a is being pulled through loops of blue yarn, the other dial needles 80 bearing red loops being retracted and not catching the red yarn at this time. Since only alternate dial needles catch the red yarn, there will be two cylinder needles separating two dial needles which have caught the yarn. 85 Due to the fact that the cylinder needles are up at this time and the red yarn passing from one dial needle to the next dial needle where it is caught must pass around two cylinder 90 needles, instead of passing directly from one dial needle to the next dial needle where it is caught, it follows that the loop of red yarn so formed will be larger than if the cylinder needles were down. Cam 4 now pulls back 95 the dial needles bearing the red yarn, as shown in position 165, through the blue loop previously formed in the last knitted row. See Figure 10 where the red loop 166 is pulled through the blue loop 167. Cam 7 100 now pushes outwardly to a slight extent those dial needles just retracted by cam 4, as shown to the right of needle 165 in Figure 7^a.

The white yarn carrier is the next to pass 105 and white loops are formed by the cylinder needles but not by the dial needles. All the cylinder needles already being up, the white 110 yarn is caught by them, as shown to the left of Figure 7^b, and cam 82 causes them to be subsequently lowered. The red yarn is on 115 the outside of the cylinder needles, being pulled in by alternate dial needles. The cylinder needles, due to cam 82, now pull the white yarn down on the inside of the red 120 yarn, and the red yarn then slips over and back of the cylinder needles as the cylinder needles are brought up again due to special cam 83. Position 168 in Figure 7^b shows the cylinder needles lowered due to cam 82, the 125 needles having been lowered on the inside of the red yarn, while position 169 shows the needles raised on the outside of the red yarn due to action of cam 83. This twisting of the white yarn around the red yarn effectively locks these two yarns together and aids in the prevention of drop stitches and the like.

The raising of the needles by special cam 83 causes the white yarn to come in contact 130 with special shoulders on the cylinder needles

which raise the white yarn, separating it from the red yarn, as shown in position 169, Figure 7^b. This separation of the white and red yarns allows the alternate dial needles projected outwardly by cam 8' to enter between the red and white yarns, the white yarn being above the dial needle and the red yarn below the dial needle, as shown in position 169. These alternate dial needles projected outwardly by cam 8' are now ready to catch the blue yarn, as shown to the left of Figure 7^c. This, as shown later in Figure 7^c, pulls the blue yarn between the red and white yarns. See Figure 10, where blue loop 167 is shown pulled between white loop 170 and red loop 171.

Beginning with position 172, cam 8' comes into play to project alternate dial needles in between the white and red yarns. At the same time the cylinder needles are being lowered by cam 84, as shown at the extreme right of Figure 7^b. This transfers the white yarn from the cylinder needles to the dial needles. At the left of Figure 7^b the white loops are formed by the cylinder needles, while at the right of Figure 7^b the cylinder needles have relinquished their hold on the white yarn and the white yarn is now being carried on the shanks of the dial needles. This transfer of the white yarn from the cylinder needles to the dial needles is an important step in the production of this novel stitch.

The blue yarn carrier now passes and the projected dial needles catch the blue yarn, as shown at the point 173, Figure 7^c, after which these needles are pulled back by cam 4', bringing the blue loop between the red and white yarns, as shown in Figure 10. At the right of Figure 7^c, the fabric just knitted has been pulled over the cylinder edge and the cycle of operations just described will then be repeated.

As will be observed by reference to Figure 10, the operation on the white yarn, as shown in Figure 7^b, serves to twist the red yarn around the white yarn, thereby providing a substantial interlocking of the yarns which will aid greatly in preventing the fabric from unraveling due to an accidental tear. See, for example, in Figure 10 where the red yarn at each end of the red loop 182 is wrapped around the white yarn at the points 180 and 181. If, for example, the red yarn loop 182 should break, the break would not run through the fabric because the broken ends would be held by their being wrapped around the white yarn at points 180 and 181. This, therefore, aids in the prevention of drop stitches.

Another special feature of the new stitch shown in Figure 10 is that it is an excellent imitation of hand knitting and is therefore of pleasing appearance.

65 Special attention should be called to the

reason why the red yarn loops, as loop 182 of Figure 10, are much larger than the blue loops, such as loop 167. This is because when the red loops are being formed the cylinder needles are up and each red loop must pass on the outside of two cylinder needles, as shown in Figure 7^a at the right. However, when the blue loops are being formed, as shown in Figure 7^c, the cylinder needles are down and the blue yarn passes straight from one dial needle to the third dial needle. This, therefore, makes each blue loop smaller than a red loop. This also adds to the pleasing appearance of the fabric.

Another important feature of this new stitch is that it enables a selvage to be formed which will not cause an unraveling of the fabric. The cloth made by this new stitch can be cut at a desired point and the cut edge will require no special attention to be used as the end of a garment, that is, no special hem or stitching will be needed to give it a finished appearance free from danger of unraveling. For example, suppose that in Fig. 10 we pull the blue yarn 190 out of the fabric, and then cut the red loops at the points 191 across the fabric. This will leave small fragments of the red yarn which can readily be pulled out from each side of the separated fabric leaving a clean separation of the fabric along the line 192 such that no unraveling or drop stitches will be produced. The same result may be obtained somewhat more quickly by first pulling out the blue yarn 190, cutting the red yarn forming the loops crossing line 192 at two remote points in the fabric, and then pulling out the cut red yarn to obtain the separation along the desired width of the fabric. This saves the labor of pulling out the fragments of the cut red yarn one portion at a time. It is therefore quite convenient to have several rows of this new stitch at each end of the fabric or at definite intervals in the cloth because the cloth can be separated in the new stitch portion without any unraveling or drop stitches being formed. Hence, in Fig. 8 the border of the goods is made with the new stitch, while the main central portion is of the pattern type.

It will be noted that the machine of Fig. 1 is arranged to knit the pattern portion of the fabric by the dial needles instead of by the cylinder needles. This is preferable because a closer spacing of the needles can be made resulting in a finer, more closely woven fabric. This is due to the fact that the dial needles spread apart going from their knitting points to their outer ends, thus providing sufficient spacing at their outer ends for the independent control of each needle while still having the needles close together at their knitting points. The cylinder nee-

dles, on the contrary, are parallel to each other and have the same spacing at each end.

It will be understood that the grooves in which the dial needles and control members work are of suitable depth and dimensions to enable these members to be accurately controlled and regulated in the cycle of operations in which they function. The proper proportioning and dimensioning of the various parts of the machine of Figure 1 may readily be determined by a skilled mechanic and it is not believed that a more detailed description of the construction of the machine need be given herein.

Figure 6^e shows an alternative type of control rod for the dial needles which may be employed in place of the type 45 shown in Figure 6^a. Whenever the portion 185 strikes a cam which pushes it outwardly, the control arm 183 through the coiled spring 184 will be pushed outwardly to come in contact with the pattern paper and will pass through the pattern paper if an aperture is present. If no aperture is present, spring 184 will be elongated and after the cam which is pressing member 185 outwardly has passed, the member 185 will take an advanced inward position ready to function as in Figures 6^a, 6^b, 6^c and 6^d.

Figures 12, 13 and 14 represent a machine of the same general type as disclosed in Figure 1, having both dial and cylinder needles and capable of forming both the pattern stitch as well as the new stitch above described, but the machine differs from the machine of Figure 1 in that only one pattern drum is required for controlling the dial needles around the entire circumference of the machine. Spider 200 is similar to spider 40 of Figure 1. The operation can probably be best explained by reference to Figures 14^a-14^c. The apertured drum 201 is provided with a pattern paper 202 which passes over the drum as in Figure 6^a. The control mechanism for each dial needle comprises a member 203 having three arms 204, 205 and 206 rotatably pivoted on a stationary shaft 208. Attached to the end of arm 205 is a long flexible wire 209, such as a steel piano wire, passing through a tubing 210, which is made of braided wire or a plain metal tube for providing a channel for wire 209. The tube 210 and wire 209 should be designed to reduce lost motion to a minimum between the ends of wire 209. The other end of the wire 209 is fastened to the end of control member 211, which actuates the needles, as will be described later. The spring 213, compressed between a shoulder on the stationary annular plate 212 and shoulder 214, serves to exert a normal pull on the wire 209, which tends, when the spring is compressed, to move arm 205 in a counter-clockwise direction. This tends to keep the end of arm 204

resting on the rotatable cam surface 216. This cam is a long rotatable cylinder having an irregular surface, as shown in cross section in Figure 14^a. The depression in this cylinder takes a diagonal course around the cylinder from one end to the other in order that the arms 205 for the various dial needles will ride in the depression successively one at a time. This cylinder 216 is rotated counter-clockwise due to cog 217 contacting with the worm drive 218 mounted on a vertical shaft, at the other end of which is cog 219 meshing with teeth around the outer edge of the lower rotatable annular plate 220. The drum 201 is driven by a cog wheel 221 meshing with a cog wheel 222 mounted on the same shaft as cylinder 216.

As the cylinder 216 rotates counter-clockwise, the end of arm 204 rides on the cam surface. In Figure 14^a it is shown riding on the part of greater diameter, which puts the arms 204, 205 and 206 in their maximum clockwise position. As soon as cylinder 216 has rotated sufficiently to allow arm 204 to rest on the part of smaller diameter, arm 205 pushes on wire 209 and arm 206 moves towards the pattern paper. If there is no aperture in the paper opposite pin 225, only a slight motion of wire 209 and control arm 211 is produced. If there is an aperture, a relatively larger motion of control member 211 is produced. In Figure 14^a, a dial needle 227 is shown resting in a groove in the stationary annular plate 212. If now the cylinder 216 is rotated so that arm 204 rides a depression and pin 225 of arm 206 enters an aperture in the paper pattern and drum, control member 211 will be pushed forward, as shown in Figure 14^b, and a cam 229 coming around in a counter-clockwise direction will raise control members 211, as shown in Figure 14^c. This raising brings control member 211 against pin 230, which will in turn raise the butt end of the needle. This will raise the needle a sufficient distance that cam 231 coming around will contact with the needle butt and push the needle inwardly so as to catch the yarn and perform its knitting functions. After the passage of cams 229 and 231, cam 232 (Figure 14^c) will cause the needle to be retracted and thereafter member 211 will fall back into place, allowing pin 230 to drop and cam 228 coming around to repeat the cycle will push the butt end of the needle into its groove, as shown in Figure 14^a.

Power for driving the machine of Figure 12 may be obtained in the same manner as in Figure 1, and is shown at the position marked 240.

The tubing 210 for all the dial needles pass through apertures in a supporting plate 241 and then are suitably curved around the machine, finally passing through an aperture in a stationary ring 242, which sur-

rounds the machine, the tubing ending in spirit of this invention as defined in the ring 242 while the wire passes on to the appended claims.

5 It is to be understood, of course, if the arm 204 passes over the larger diameter to the smaller diameter of the drum 216 and pin 225 encounters no aperture in paper 202, then the movement of control member 211 resulting therefrom is insufficient to cause the end of member 211 to be raised by cam 229 so that the pin 230 and the butt end of the needle are not raised, and consequently the needle will not be pushed forward to 15 catch the yarn. It will therefore be apparent that when one of the arms 206 is turned counter-clockwise to enter an aperture in paper 202, the needle associated therewith will enter into the knitting, but 20 if no aperture is present, the associated needle will not enter into the knitting at that particular time. It therefore follows that the dial needles so controlled may be made to form the knitting illustrated in 25 both Figures 10 and 11 in combination with the cylinder needles of Figure 12, the change from one type of knitting to another type being made by a cylinder cam operation, as described in connection with Figures 2 30 and 4. The machine of Figure 12 therefore will perform the same functions as the machine of Figure 1 but is somewhat more simple to operate in that the machine of Figure 1 requires seven paper patterns, 35 while the machine of Figure 12 requires only one paper drum. Otherwise the two machines are similar in operation.

One other minor difference may be pointed out. The drum 201 and the cam surface 40 216 are continuously rotated, while the drum for the paper pattern for the machine of Figure 1 is intermittently operated. The continuous operation of the drum 201 is possible because the slots in the paper and 45 the drum are made considerably longer than the diameter of the entering pins 225 and these apertures in the drum are placed on a slightly diagonal line so that the drum can still move while one or more pins 225 remain inserted in the apertures. The size 50 of the apertures to be made in the drum and paper to enable this continuous rotation of drum 201 may be readily determined after due consideration of all the factors 55 involved.

It is to be understood that the various parts of the machines of Figures 1 and 12 may be appropriately supported according to arrangements well known in the art. 60 Such features form no part of the present invention and have not been described in detail.

It is furthermore to be understood that this invention may possess many forms differing widely from those above described 65 without departing in any wise from the

spirit of this invention as defined in the appended claims.

The invention claimed is:

1. A knitting machine of the circular type comprising dial needles horizontally arranged, a group of rotatable cams rotating in a horizontal plane for controlling the movements of said needles, a control member for each needle, a second group of cams rotating in a horizontal plane for causing 70 said control members to move said needles, a perforated pattern, means for moving said pattern as the knitting progresses and plungers controlled by the presence or absence of perforations in said pattern for 80 moving said members into the path of said second group of cams.

2. A circular knitting machine comprising dial needles arranged in a horizontal plane, a control member for each needle 85 adapted at times to move its associated needle to such a position as to engage in the knitting operation, a perforated sheet, means cooperating with said sheet for moving said member to a forward position, rotatable cam means contacting with said member for causing the further movement of said member to cause a corresponding movement of the associated needle, and additional rotatable cam means contacting with said 90 needle in its advanced position for causing said needle to enter into the knitting.

3. A knitting machine of the circular type comprising dial needles and automatic means for securing an independent control 100 of each of said needles, said means comprising a control member for each needle, rotatable cam means for pushing forward pre-selected needles, a second rotatable cam means acting on said control means for 105 bringing preselected needles under the control of said first cam means, a perforated drum rotatable about a fixed axis, a movable sheet around said drum and having perforations arranged to determine the 110 pattern of the fabric to be knitted, and means controlled by said sheet for causing a predetermined fraction of said control members to come under the control of said second cam means.

4. A knitting machine of the circular type comprising both dial needles and cylinder needles, a plurality of yarns of different types to be knitted by said machine, cams operating to cause said cylinder needles to knit loops of only one type of yarn and said dial needles to knit loops of two other types of yarn to form a fabric of one kind of stitch, and cam means for causing said cylinder needles to form loops of the three mentioned types of yarn, while causing said dial needles to form loops of only two types of yarn to form a stitch of a different type.

5. A knitting machine of the circular type comprising both dial needles and cylinder 130

- needles, a plurality of yarns of different types to be knitted by said machine, cams operating to cause said cylinder needles to knit loops of only one type of yarn and said 5 dial needles to knit loops of two other types of yarn to form a fabric of one kind of stitch, cam means operating to cause said cylinder needles to form loops of the three mentioned types of yarn while causing said 10 dial needles to form loops of only two types of yarn to form a stitch of a different type, and automatic means for changing at predetermined times from one type of stitch to the other.
- 15 6. A knitting machine of the circular type comprising both cylinder and dial needles for knitting loops of different colors of yarn, shoulders on said cylinder needles near their latches, and means for causing said shoulders 20 to lift temporarily one yarn from a second parallel yarn, means for causing certain of said dial needles at that moment to be moved forward between said yarns to catch a third yarn, means for pulling said dial needles 25 back after the third yarn is caught, and means for lowering said cylinder needles.
7. A knitting machine of the circular type comprising both cylinder and dial needles for knitting loops of different types of yarn, 30 means for causing said dial needles to form loops of two yarns, means for causing the loop of one yarn formed by said dial needles to be larger than the loops formed from the second of the two yarns, means for causing 35 said cylinder needles to form loops of a third yarn, while interlocking said third yarn with said one yarn on each side of every loop of said one yarn, whereby at a particular point in the fabric said second yarn may 40 be pulled from the fabric and said large loops of the first yarn may be cut to form a selavage.
8. A knitting machine of the circular type comprising both cylinder and dial needles 45 for knitting loops of different types of yarn, means for causing said dial needles to form loops of two yarns of different types, means for causing said cylinder needles to be up when said dial needles are forming loops of 50 one yarn, means for causing said cylinder needles to be down when said dial needles are forming loops of the second yarn, whereby the loops of said first yarn are longer than the loops of the second yarn, and means for causing 55 said cylinder needles to form loops of a third yarn while interlocking the third yarn at each side of each loop of the first yarn.
9. A knitting machine for knitting a fabric of a plurality of yarns, comprising cylinder needles and dial needles, means for causing certain dial needles to catch one 60 yarn while intermediate cylinder needles are up so that said one yarn lies around certain of the cylinder needles, means for causing 65 said certain cylinder needles to catch a
- needles, a plurality of second yarn and be lowered after which they are immediately raised on the outside of said first yarn with their latches open, and means for subsequently causing certain dial needles to catch said second yarn and to 70 lower said cylinder needles whereby the stitch is transferred from the cylinder needles to the dial needles.
10. A knitting machine of the circular type comprising dial needles, rotating cams 75 for operating said needles, push rods for moving said needles in such positions as to be controlled by said cams, a perforated rotatable drum having a row of perforations around its periphery for a plurality of said dial needles, a perforated pattern sheet on the outside of said drum, fingers adapted to pass into the perforations in said drum at places where perforations occur both in the paper and the drum, and a flexible wire passing from each of said fingers to one of said push rods for controlling the movement of 80 said push rods.
11. A knitting machine for knitting a fabric of a plurality of yarns, comprising cylinder needles and dial needles, means for causing certain dial needles to catch one yarn while the intermediate cylinder needles are up whereby the said intermediate cylinder needles are on the inside of said one yarn at 90 that instant, means for causing certain of said cylinder needles to catch a second yarn and for immediately lowering said cylinder needles whereby the second yarn is pulled down on the inside of said first yarn, means for causing said cylinder needles to be immediately raised whereby said second yarn is pulled up on the outside of said first yarn, and means for subsequently transferring 95 said second yarn from the cylinder needles to the dial needles.
12. A knitting machine of the circular type comprising dial needles, yarn carriers for feeding to said machine yarns of different types, rotatable cams for controlling the operations of said needles, a push rod individual to each needle for bringing each needle under the control of said cams, a perforated drum rotatable about a fixed axis and having a row of perforations around its periphery for each of a plurality of said needles, a perforated pattern sheet passing around said drum, and means for penetrating said drum at places where perforations in said drum and said sheet coincide for controlling the movements of said push rods.
13. A knitting machine of the circular type comprising a circular row of dial needles, rotating cams for operating said needles to produce knitting by said needles, a push rod for each of said needles for moving its associated needle into such position as to be controlled by said cams, said rods being radially and symmetrically spaced around substantially the entire cir- 125 130

- 5 cumference of said machine, a perforated rotatable drum having a row of perforations around its periphery for each dial needle, a perforated pattern sheet on the outside of
 10 said drum, fingers adapted to pass into the perforations in said drum at places where perforations occur both in the paper and the drum, and a flexible wire passing from each of said fingers to one of said push rods for
 15 controlling the movement of said push rods.
14. A knitting machine of the circular type comprising a circular row of needles, cam means for operating said needles, an actuating member for each of a plurality of
 20 said needles for independently moving each needle into such position as to be controlled by said cams, a perforated pattern, fingers adapted to pass into perforations in said pattern, a flexible wire connected between
 25 each of said fingers and one of said actuating members, a tubing surrounding each wire in which the wire may freely slide to faithfully impart the motion of each finger to the associated actuating member with negligible lost motion, and means for periodically causing said fingers to contact with or pass through
 30 said pattern depending upon the absence or presence of a perforation.
15. A knitting machine comprising a circular row of needles, cam means for actuating said needles to produce the desired knitting operations, a perforated pattern having perforations corresponding to each of a plurality of said needles, means for continuously
 35 moving said pattern at a substantially constant speed during the knitting operations, and means cooperating with said pattern while moving at its said constant speed for causing the perforations in said pattern to control the knitting operations of a plurality of
 40 said needles.
16. A knitting machine according to claim 15 in which said cooperating means comprises a control member for each of a plurality of said needles, a plunger individual to each of a plurality of said needles adapted to pass through perforations in said pattern, and a flexible wire connecting each plunger with one of said control members.
- 50 17. A knitting machine according to claim 15 in which said cooperating means comprises a plunger individual to each of a plurality of needles and adapted to pass through perforations in said pattern, said perforations being elongated to allow for the movement of said pattern while a plunger is in one of said perforations.
- 55 18. A knitting machine comprising a circular row of needles, and means for controlling the knitting operations of a plurality of said needles, said means comprising an actuating member for each needle, a perforated drum adapted to support a perforated pattern, a plurality of plungers adapted to pass through perforations in said
 60 pattern and drum, coupling means between each of said plungers and one of said members, cam means for periodically actuating said plungers to cause them to contact with said pattern or pass through perforations in said pattern and drum, and means for rotating said drum and said cam means at a substantially constant speed.
19. A knitting machine comprising a circular row of dial needles with their latched ends pointed inwardly, an actuating member individual to each of a plurality of said needles, a perforated pattern having perforations for determining individually the knitting operations of a plurality of said needles, a plurality of plungers adapted to pass through perforations in said pattern, a flexible wire connected between each of said plungers and one of said members whereby the motion of each plunger may be imparted to its associated member, a housing individual to each wire for reducing lost motion between each plunger and its associated members, and means for causing said plungers to pass through perforations in said pattern.
20. A knitting machine comprising a circular row of needles, an individual control member for each of a plurality of said needles, a flexible wire of substantial length connected at one end to one of said control members, a similar wire for each of the remaining control members, said wires being curved so that near their opposite ends they are parallel to each other in a common plane, pattern mechanism for controlling said wires at their last mentioned ends, and a closely fitting housing for each of said wires whereby a longitudinal movement of said wires is imparted to said members.
21. A knitting machine in accordance with claim 20 in which one of said members and one of said wires are provided for substantially every needle of said row, a closely fitting housing for each wire, and a plunger at one end of each wire adapted to penetrate perforations in said pattern.
22. A knitting machine of the circular type comprising dial needles, rotatable cams for controlling said needles, a control member contacting with each needle for determining when its associated needle will be controlled by said cams, a perforated pattern movable about a fixed axis, and spring actuated plungers adapted to pass through said perforations for controlling said members, one of said plungers being attached to each of said control members.
23. A knitting machine of the dial type comprising a circular row of needles, a dial in which said needles are radially disposed with their hooked ends projecting inwardly, a push rod individual to each needle and supported by said dial, said rods also being radially disposed and arranged in a circle

outside the circle of said needles and adapted at times to contact with said needles, yarn carriers adapted to supply yarn to the inner ends of said needles, rotatable cams for advancing and retiring said needles, rotatable cams for causing said rods to determine the control of said needles by said first cams, the outer ends of said rods due to the radial disposition of said needles and rods being separated from each other greater distances than the inner hooked ends of said needles, and means comprising a perforated pattern drum for providing for the individual control of a plurality of said rods for each passage of said yarn carriers, said drum being mounted on a fixed axis.

24. A knitting machine according to claim 23 in which said means comprises plungers adapted to pass through perforations in said drum, and flexible wires connect each plunger to a push rod.

25. A knitting machine comprising a dial, needles radially disposed in grooves in said dial, the hooked ends of said needles being the inner ends, a group of rotatable cams rotating in a horizontal plane for controlling the movements of said needles, a control member for each needle, a second group of cams rotating in a horizontal plane for causing said control members to move said needles, a perforated pattern, means for moving said pattern as the knitting progresses, and plungers controlled by the presence or absence of perforations in said pattern for moving said members into the path of said second group of cams.

26. A knitting machine comprising a dial, needles radially disposed in grooves in said dial, the hooked ends of said needles being the inner ends, a group of rotatable cams rotating in a horizontal plane for controlling

the movements of said needles, a control member for each needle adapted to raise the butt ends of said needles into the path of said group of cams, a second group of cams rotating in a horizontal plane, means responsive to said second group of cams for causing said control members to move said needles, a perforated pattern, means for moving said pattern as the knitting progresses, and plungers controlled by the presence or absence of perforations in said pattern for moving said responsive means into the path of said second group of cams.

27. A knitting machine comprising a dial, needles radially disposed in grooves in said dial, the hooked ends of said needles being the inner ends, a group of rotatable cams rotating in a horizontal plane for controlling the movements of said needles, a control member for each needle, a second group of cams rotating in a horizontal plane for causing said control members to move said needles, a long thin strip of flexible material having a pattern thereon having a characteristic varying in a manner in which it is desired to vary the knitting of a plurality of said needles, and means controlled by the varying characteristic of said pattern for moving said members into the path of said second group of cams.

28. A knitting machine in accordance with claim 27 in which said pattern material is mounted on a rotatable drum, rotating on a fixed axis, and in which said means comprises a plurality of fingers contacting at times with said pattern material, each of said fingers being connected to one of said control members.

In witness whereof, I hereunto subscribe my name, this 1st day of July, A. D., 1924.

VINCENT LOMBARDI.
